C. L. TAGGART.
COMBINED LETTER SHEET AND ENVELOP.
APPLICATION FILED APR. 3, 1918.

Patented May 13, 1919.

ATTORNEY

UNITED STATES PATENT OFFICE.

CLAUDE L. TAGGART, OF JAMESTOWN, NEW YORK.

COMBINED LETTER-SHEET AND ENVELOP.

1,303,412.

Specification of Letters Patent. Patented May 13, 1919.

Application filed April 3, 1918. Serial No. 226,513.

To all whom it may concern:

Be it known that I, CLAUDE L. TAGGART, a citizen of the United States, residing at Jamestown, in the county of Chautauqua 5 and State of New York, have invented certain new and useful Improvements in Combined Letter-Sheets and Envelops, of which the following is a specification.

The primary object of this invention is 10 the provision of an envelop or like receptacle for receiving a letter sheet or other matter commonly transmitted through the mails, and which envelop is of such formation as to be readily opened without requiring the use of any implement and without 15 endangering the contents or resulting in injury thereto.

Specifically considered, the invention has 20 for its object to provide a combined envelop and letter sheet which constitute parts of the same blank, the latter having sealing tabs which may be gummed or made secure by folding and tucking one tab over the other.

25 The invention also has for its object to provide simple means whereby a return notice may be prominently displayed and whereby the address and the name may be written at one and the same operation and 30 in proper position, both upon the envelop section and the opening portion of the letter sheet.

The invention furthermore provides a 35 combined envelop and letter sheet which is adapted to be folded in a variety of ways and which embodies sealing tabs disposed in such relation as not to add materially to the cost of the usual letter sheet and which is considerably less than the combined cost of 40 a letter sheet and envelop.

The drawing illustrates a preferred embodiment of the invention, however, it is to be understood that in adapting the same to meet different conditions, various changes in 45 the form, construction, and operation of the device may be resorted to without departing from the nature of the invention as claimed hereinafter.

In the drawings:—

50 Figure 1 is a detail view of the blank from which the combined letter sheet and envelop is formed.

Fig. 2 is a detail view showing the manner of tucking in the last fold.

55 Fig. 3 is a detail view showing the manner of providing the address on the en-

velop and the superscription on the letter sheet.

Fig. 4 is a detail perspective view of a 60 modification.

Corresponding and like parts are referred to in the following description and indicated in all the views of the drawings by like reference characters.

The combined letter sheet and envelop is 65 formed from a blank substantially as shown in Fig. 1 and which is adapted to be folded in a manner substantially as indicated by the broken lines. The blank is preferably of oblong or rectangular shape and is provided at one end with a plurality of tabs 70 1, 2, and 3 which are separated from the body of the blank or sheet by a line of perforations as indicated at $a-a$. This perforated line $a-a$ may be provided in any 75 manner, the purpose being to facilitate the separation of the tabs when it is required to open the envelop by the person to whom the same is addressed. The blank sheet is adapted to be folded on the transverse lines 80 $b-b$ and $c-c$ and on the longitudinal lines $d-d$ and $e-e$. The tabs 1 and 3 are of a length corresponding to the width of the sections comprised between the outer edges 85 of the blank and the adjacent lines of fold represented by $d-d$ and $e-e$. These tabs 1 and 3 are gummed so as to effectually seal the sheet when folded into the form substantially as indicated in Fig. 2. The 90 middle tab 2 is somewhat longer than the tabs 1 and 3, i. e., it projects from the blank to a greater extent and the portion projecting beyond the tabs 1 and 3 is adapted to receive the address of the sender so that in the event of non-delivery of the 95 envelop or package it may be returned to the addresser. This middle tab is not gummed, but the tabs 1 and 3 are secured thereto by the gum or adhesive applied thereto, whereby the envelop is sealed.

100 In accordance with the present invention, the upper left hand corner portion of the letter sheet or blank is folded upon the main body of the blank as indicated in Fig. 3, and a carbon sheet 4 is interposed between the 105 folded corner portion and the body of the sheet. The address is written or otherwise provided upon the folded corner portion as indicated, and by reason of the interposition of the carbon sheet 4 between it and the 110 body of the sheet, the latter has the superscription written thereon simultaneously

with the address. This insures agreement of the address and superscription and prevents any possible mistake such as frequently arises where the envelop and letter sheets are separated and distinct parts.

After the message or other matter has been written or inscribed upon the letter sheet, the same is folded first upon the line $b-b$, then upon the line $c-c$ after which the folded sheet is again folded along the lines $d-d$ and $e-e$. When making the last fold, the lower corner portion is rolled and passed between the outermost fold and the adjacent fold as indicated in Fig. 2. This results in bringing the last fold between the second to the last fold and the middle portion or section of the sheet containing the middle tab 2. The tabs 1 and 3 are now moistened and sealed, one upon the other and to the middle tab 2. The address of the party sending the package is inscribed upon the projecting portion of the tab 2. The addressee or party receiving the package opens the same readily and with despatch by simply tearing off the tabs 1, 2, and 3 along the weakened or perforated line $a-a$ and this may be easily accomplished because of the weakened line.

In the modification shown in Fig. 4, the sheet or blank may be of any size and is provided at one end with tabs corresponding to those indicated in Fig. 1. The side tabs 1^a and 3, however, are devoid of gum or other adhesive since it is not the intention to seal the envelop in a permanent manner, but to fasten the same temporarily so that the postmaster may make a proper inspection as provided for second and third

class matter. The tab 1^a is of a length equal to the middle tab 2 and when the sheet or blank is folded, the tab 1^a is folded over the tab 3 and its outer end extends so as to be readily grasped when it is required to open the envelop to admit of an inspection thereof.

The foregoing description and the drawings have reference to what may be considered the preferred or approved form of my invention. It is to be understood that I may make such changes in construction, arrangement, and combination of parts, materials, dimensions, et cetera, as may prove expedient and fall within the scope of the appended claim.

Having thus fully described my invention, what I claim as new and desire to secure by Letters Patent, is:—

A combined letter sheet and envelop, comprising a blank sheet having a middle and side tabs at one end and foldable transversely and longitudinally, the longitudinal folds coinciding with the spaces between the tabs, the side tabs being of less length than the middle tab, the projecting portion of the latter bearing printed matter, the several tabs being foldable on one another and gummed for attachment and separated from the body of the sheet by a straight line of perforations.

In testimony whereof I affix my signature in presence of two witnesses.

CLAUDE L. TAGGART.

Witnesses:

EDWIN A. RIDELL,
A. M. LYNN.
